UNITED STATES PATENT OFFICE

2,504,970

ELECTRON DISCHARGE DEVICE

Herbert F. Engelmann, New York, N. Y., assignor to Federal Telephone and Radio Corporation, New York, N. Y., a corporation of Delaware.

Application October 3, 1945, Serial No. 620,143

2 Claims. (Cl. 250—27.5)

8

My invention relates to electron discharge devices, particularly to discharge devices of the magnetron type, and to mountings for such devices.

In most modes of operation of the magnetron, considerable quantities of electrons return to and bombard the cathode, which has, heretofore, limited the output of high frequency power to the heat dissipating capacity of the cathode. Filamentary cathodes are particularly easy to overheat and destroy by bombardment.

The conventional magnetron, further, is unstable in operation partly because of the critical value of the magnetic field that must be maintained. A slight variation of field strength, for example, near anode current cut-off may completely change the mode and the frequency of oscillation. Instability becomes particularly manifest when one tube is substituted for another in its mounting. The magnetizing means of the usual magnetron is a coil telescoped over the envelope and is entirely external to the evacuated space of the tube, so that the distances between the electrodes and the coil cannot be accurately established in manufacture.

A still further disadvantage of the conventional magnetron oscillator resides in the usually poor electrical connection between segments of the anode where each anode is "split" or divided into two or more electron collecting sections. For efficient operation at ultra-high frequencies, it is important that there be no impedance nor phase differentiation between the different sections of an anode.

An object of my invention is an improved magnetron.

Another object of my invention is an improved unitary magnetron and magnetron mounting.

Another object of my invention is a magnetron oscillator which is stable in operation.

A more specific object of my invention is a magnetron with a cathode having a high heat dissipating capacity.

Another and specific object of my invention is a magnetron tube with a relatively small gap in the magnetic circuit across the discharge space of the tube, the gap being built into the tube and hence subject to close manufacturing tolerances.

A still further object of my invention is a magnetron with simple yet impedance-free connections between the segments of the anode.

My invention is defined in the appended claims and one embodiment is described in the follow-

ing specification and shown in the accompanying drawing in which

Fig. 1 is a lengthwise sectioned view of my novel magnetron tube and its mounting and

5 Fig. 2 is a horizontal section taken on line 2—2 of Fig. 1.

The discharge device of my novel magnetron oscillator comprises a tubular cathode sleeve 1 coaxial with the circularly arranged and interleaved segments 4 and 5 of anodes 2 and 3. The envelope for the electrodes comprises glass annuli 6, 7 and 8 hermetically sealed to the metal parts of the tube. An exhaust tubulation 9 may be joined to one of the glass portions for exhaust-
ing and sealing the envelope.

ing and sealing the envelope.

The cathode, according to one important feature of my novel magnetron comprises a rigid metal sleeve or tube exteriorly sensitized with electron emitting material and adapted for indirect heating with an interior heating coil 10. By connecting one end of the heating coil to the sleeve, two lead-in conductors 11 may suffice for the cathode and its heater. The lead-ins are sealed through a glass button-type header 12. If additional support for the cathode assembly is desired, a stud may be attached to the sleeve and embedded in the header. Since the diameter of the cathode is relatively large, the ends of the sleeve are preferably closed to conserve heat and prevent random electron emission from the coil.

The magnetron anodes each comprise an annulus having spaced upstanding integral projections or segments along the inner periphery of the annulus opposite the cathode. The inner peripheries of the annuli are of the same diameter so that the anode segments may interleave and lie in a common circular surface. The anode segments are an integral part of and are supported upon annular lead-in conductors 13 and 14 sealed radially through the envelope. The outer periphery of the anode annuli press against the concentric conductors 15 and 16 of a cavity resonator or transmission line. The usual straps and complicated connections of the conventional split anode magnetron are eliminated in my tube.

45 split anode magnetron are eliminated in my tube. Accurate placement and control of the magnetic field within the annular discharge space is effected by magnetic plugs or stoppers 17 and 18 hermetically sealed through the ends of the envelope. The stoppers may be of iron, nickel, cobalt, steel or any of the paramagnetic alloys. The stoppers are round, coaxial with the cathode, terminate adjacent the ends of the cathode, and have a diameter slightly less than the inner diameter of the anode. When a magnetic field

tial is applied between the stoppers, as with a magnetic yoke 19 and current coil 20, the magnetic lines are well confined to the electron discharge space and since the pole-to-pole gap is reduced to a minimum, fringing effects of the field become negligible, extraneous magnetic effects in the space are largely eliminated, and the field is intense and stable. My improved magnetron is stable in operation and uniform as to operating characteristics. Magnetrons made according to my invention may be replaced in service without changes in mode of oscillation and without laborious readjustment of power supplies for the cathodes, anode and magnet.

The outer ends of the magnetic stoppers are preferably machined and polished to make good contact with the ends of the yoke. One leg of the yoke may be hinged as at 21 to permit easy replacement of the tube.

The stopper in the lower or base end of the envelope is conveniently annular in shape to accommodate the insulating header and the cathode leads, and to shape the magnetic field to the annular anode-cathode space. If desired the inner face of the upper stopper may be recessed to provide a rim opposite and complementary to the end of the lower stopper. Accordingly, the pole pieces of my improved magnetron may be brought close to the discharge space to accurately localize the field in the space. Less magnetizing power is required for a given field strength in the gap and less disturbance of the field is possible from extraneous sources.

My improved magnetron is simple and inexpensive to make, being adapted to the manufacturing technique of the conventional radio receiving tube. The header is first press molded in the lower stopper with the cathode leads. The cathode sleeve is then assembled with its heater coil and their two connections spot welded to the inner ends of the leads. This subassembly may then be telescoped with the glass rings 6, 7 and 8 and metal annuli 13 and 14, conventional jigs being used for accurately spacing and holding the parts in alignment while the rims of the glass rings are melted and sealed to the adjacent metal surfaces. In case the glass is "hard" and the stoppers are of iron, it may be expeditious to make the glass-to-iron seals with pleated copper rings 22, which are feathered along one edge for the glass seal, the other edge being easily brazed vacuum tight to the iron.

An important feature of my magnetron oscillator is its cavity resonator exterior of tube envelope, and the easy adjustability of the chamber length. Concentric tubes or "lines" 15 and 16 make contact, throughout the peripheries of their upper ends, with the rims, respectively, of the anode annuli 13 and 14. The very source of high frequency electromotive force is accordingly effectively brought to the end of the resonator, with no resistive losses and with no impedance or phase shift. Yet, notwithstanding the structural compactness of oscillator, the discharge device may be removed and replaced as a conventional radio receiving tube in its socket. One advantage of the resonant chamber outside the tube envelope is its easy adjustability. Piston 23, with spring fingers, may be slid along the annular cavity with piston rods 24. Since one current maxima is at the short circuited end of the line, a current pick up coil 25 may be carried on the piston and exteriorly connected by means of twisted conductors in the piston rod. Alternatively, a capacity probe, not shown, may be inserted into the cavity at, say,

a point of voltage maximum to couple the oscillator with its load circuit. The tubes 15 and 16 could of course be extended into the endless conductors of a coaxial cable.

In operation, the anode voltage and the magnetic field strength are preferably adjusted so that space current cut-off just occurs, whereupon the electrons bunch and travel in circular paths about the cathode in planes substantially perpendicular to the axial line of the tube. Such an orbit carries the electrons successively past the segments of anodes 2 and 3, and as the electron transit time between segments approaches the resonant frequency of the connected tank circuit 15-16, the voltage induced in one set of segments, 4, becomes 10 180 degrees displaced from the voltage induced in the other set, 5. Whether this or other modes of operation be employed, each segment of either anode delivers in-phase power to the adjacent end 15 of the concentric line, 15 or 16. The number of segments per anode or the size of the anodes are not limited by any particular mode of oscillation, and, in fact, as the anode is made larger, with more segments, the anode supply voltage becomes 20 proportionately less. Further, because of the low impedance of the connections between the segments and the resonant chamber, the decrements 25

30

1
(Q)

of the circuits are low and the electric coupling is close between the anodes and frequency determining means. Accordingly, the oscillator may be tuned by the piston 23 over a wide range of frequencies without loss of control of the electron oscillations.

My invention extends the power range of the 40 magnetron by permitting the use of a large indirectly heated cathode without disproportionately increasing the anode voltage. My magnetron can be manufactured inexpensively, yet with close tolerances, even in the magnetic circuit. The 45 built-in magnetic gap insures stable operation, and uniform characteristics as between tubes. Stability, further, flows from my novel way of electrically joining the anode segments to eliminate unwanted phase differences.

I claim:

1. An electron discharge device comprising an indirectly heated cathode sleeve, a flat metal annulus disposed in a plane normal to the axis of 55 said sleeve, a second annulus with a larger outer peripheral diameter parallel to and spaced from the first mentioned annulus, each annulus having integral upstanding projections along its inner periphery and mounted in a cylindrical surface 60 concentric with the surface of said sleeve, the projections of one annulus alternating, circumferentially, with the projections of the other annulus, cylindrical stoppers of magnetic material coaxial with said sleeve and closely disposed to 65 opposite sides of the annular space between said sleeve and said projections, and insulating envelope wall portions hermetically sealed between the faces of said annuli and the sides of said stoppers.

2. The electron discharge device defined in 70 claim 1, in which said cylindrical stoppers are of a metal principally of iron and which further includes rings of thin sheet metal with circumferential pleated folds, each of said rings being hermetically sealed along one edge to one of said

stoppers and along its other edge in one of said insulating envelope wall portions.

HERBERT F. ENGELMANN.
